FREE PISTON ENGINE

Raoul Pateras Pescara, Paris, France

Application April 23, 1938, Serial No. 203,927
In Luxemburg April 29, 1937

19 Claims. (Cl. 230—56)

The present invention relates to free piston machines and it is more especially, although not exclusively concerned, among these machines with free piston auto-compressors, that is to say 5 machines of the free piston type adapted to supply compressed air.

The chief object of the present invention consists in providing a machine of this type which is better adapted to meet the requirements of 10 practice than the usual machines of the same type made up to the present time, and in particular in improving the efficiency of said machines.

The essential feature of the present invention consists in the provision of means for injecting, 15 into the compressor part of said machines, an amount of liquid variable, preferably automatically, as a function of one of the working or adjustment characteristics of said machines.

Among the characteristics which may be taken 20 into account for influencing the quantity of liquid thus injected into the compressor part of the machine, I may, for instance, use the following: amount of compressed air delivered per stroke of the pistons, delivery pressure, feed pressure, 25 one of the temperatures of operation, and so on.

According to another feature of the present invention, while injecting a certain amount of liquid into the compressor part of the machines of the type above mentioned, I cause the point of 30 injection to vary, preferably in an automatic manner, as a function of one of the working characteristics of said machines, for instance as a function of the suction pressure thereof.

Other features of the present invention will 35 result from the following detailed description of some specific embodiments thereof.

Preferred embodiments of the present invention will be hereinafter described, with reference to the accompanying drawings, given merely by 40 way of example, and in which:

Fig. 1 shows in a diagrammatic manner, and in partial view, a free piston auto-compressor made according to a first embodiment of the present invention;

Fig. 2 shows, on an enlarged scale, and in partial view, another embodiment of the auto-compressor according to the invention;

Fig. 3 is a diagram of operation of the auto-compressor shown by Fig. 1;

Fig. 4 is a partial sectional view showing another embodiment of a compressor made according to the invention;

Fig. 5 is a diagram of operation corresponding to the embodiment of Fig. 4.

Finally, Fig. 6 is a partial sectional view of

still another embodiment of an auto-compressor made according to the invention.

Although, in the following description with reference to the drawings, I have shown the specific features of auto-compressors of the type 5 having free pistons, I wish it to be well understood that the general principles of my invention illustrated by these examples also apply to other kinds of free piston machines.

Machines of the kind above referred to may 10 be constructed, as for their general structure, in any conventional or other suitable manner, for instance they may be of the type in which the compression of air takes place in two distinct stages of compression.

For instance, as shown in a diagrammatical manner by Fig. 1, an auto-compressor may be made as follows:

I provide a motor cylinder 101, and in this cylinder two pistons 102 and 102' cooperate in 20 such manner as respectively to uncover, near the ends of their outward strokes, inlet ports 103, and outlet ports 104.

These motor pistons 102 and 102' are associated, through piston rods 3 and 3', with compressor pistons 2 and 2'. The first of these last mentioned pistons, to wit 2, is mounted in a low pressure cylinder 4, and the other is slideable in a high pressure cylinder 4' fed with air from the low pressure portion of the machine.

This low pressure portion of the machine is provided, on the one hand, with a feed conduit 54, provided with an inlet check valve 55, and, on the other hand, with a discharge conduit 6, provided with an outlet check valve 5.

Likewise, the high pressure portion of the machine is provided with an inlet check valve 55' and with a discharge check valve 5'.

In a general manner, it is a known fact that it is advantageous, in air compressors, in order 40 to reduce to a minimum the power necessary for ensuring compression and delivery of the compressed air, to carry out the compression so that it is as isothermal as possible. It has already been endeavoured to obtain this result, in compressors of the type in which the pistons have a constant stroke, by injecting into the compressed

air a finely atomized liquid, either during the compression and delivery of said air or between the two stages of compression, the vaporization of this liquid having for its effect to lower the temperature of the compressed air and therefore to reduce the power necessary for ensuring the compression.

In order to obtain satisfactory results from 55

this operation of the machine, it is necessary to ensure that the amount of liquid injecting into it should not exceed the saturation limit for compressed air, as otherwise condensations would take place, with the consequence of an unsatisfactory working of the machine.

Now, a free piston auto-compressor is a machine the characteristics of operation of which, such for instance as its output (determined by the amplitude of the strokes of the movable elements thereof) its delivery pressure or temperature, its suction pressure or temperature, are liable to vary and actually vary in the course of the operation of the machine, these variations corresponding to variations of the mass of air compressed at each compression stroke, and consequently to variations of the amount of water necessary for saturating this mass of air.

According to the essential feature of the present invention, I inject, into the compressor part of said auto-compressor, an amount of liquid variable, preferably in an automatic manner, as a function of one of the adjustment or operation characteristics of said machine.

It will be readily understood that, by proceeding in this manner, I can ensure that the amount of liquid which is injected (which liquid will be supposed to consist of water in the following description) is always the optimum amount whatever be the variations of the mass of air compressed for each compression stroke of the machine.

With this object in view, according to a first embodiment of the present invention (which is to be preferred when the auto-compressor is to work with constant values of the suction and delivery pressures) I vary the amount of water that is injected into the compressor as a function only of the amount of air compressed for each stroke of the machine, that is to say as a function of the amplitude of the delivery strokes of the movable elements of the machine. The injection of water may be effected into any suitable portion of the compressor part of said machine, for instance into cylinder 1 (as shown by Fig. 2, or as shown by Fig. 4) into an intermediate reservoir, or again, as shown by Fig. 1, into the delivery pipe 4 of the low pressure stage of the machine, after the outlet valve 5 thereof.

I may then devise the elements of the system in such manner that the water injection takes place during the delivery period, or during the compression period, or even during the suction period.

I have shown in Fig. 3 the curves $a-b-c-d$ representing the cycle of compression of an auto-compressor for the maximum output of compressed air.

If the injection of water is to take place during the delivery period $a-b$ (case of Fig. 3), the system must be devised in such manner that the amount of liquid that is injected varies according to a law which corresponds to an increase of said quantity when the variable delivery stroke increases. For instance the amount of liquid injected is proportional to the amplitude of said stroke, in which case, said amount is represented by the ordinates of a straight line $m-n$, the amount of water that is injected being zero at m (where no compressed air is delivered) and maximum at n (where the amount of compressed air that is delivered is maximum).

There exist many embodiments of mechanisms for determining the amount of water injected into the compressor as a function of the ampli-

tude of the delivery stroke. For instance, I may make use of the specific arrangement illustrated by Fig. 1 of the accompanying drawings.

In this embodiment, a prolonged portion, or extension of piston rod 3 constitutes a cam 6 adapted to coact with the piston 7 of a control device, such as a pump 8 feeding water to an atomizing element 9 disposed, for instance, in the delivery conduit 4 of the compressor.

The length of this cam 6 is measured in such manner that it corresponds to the maximum length of the delivery stroke $a-b$.

This cam is preferably arranged in such manner that it starts acting upon piston 7 as soon as the delivery stroke begins.

If now the injection of water is to take place during the compression period and if it is also assumed that the working pressures are constant, which corresponds to constant lengths of the compression stroke $d-a$, it is advantageous, in order to control the amount of water that is injected in accordance with the length of the delivery stroke, to have recourse to another feature of the present invention, which has not yet been set forth and which consists in accumulating during one delivery stroke an amount of water which is a function of the amplitude of said stroke (being for instance proportional to this amplitude) and in injecting this amount of water but subsequently, for instance, in the present case, only during the next compression stroke.

Such an arrangement is preferably made as illustrated by Fig. 2.

In this embodiment, a cam surface 6, carried by an extension of rod 3, is caused to coact with the piston 7 of an accumulation pump 8' including chamber 10 of variable volume, and an accumulator piston 10' subjected to the action of a spring 11.

The injection of water, which takes place for instance into cylinder 1, is controlled by a valve 12, subjected to the return action of a spring 13. This valve 12 coacts with an abutment 14 carried, preferably in an adjustable manner, on the piston rod 3, the whole being arranged in such manner that valve 12 ensures its own distribution, which means that it uncovers the feed passage for water under pressure once it is fully depressed (near the end of the suction stroke of the pistons).

This valve will then be kept in this depressed position by the pressure of the water that is injected, until the end of the injection, at which time the valve comes back onto its seat, where it remains until the end of the next suction stroke.

In the preceding description, it has been assumed that the delivery and suction pressures of the auto-compressor remained constant.

When at least one of these pressures varies, the mass of compressed air delivered for each stroke of the machine varies also. I may therefore, advantageously, in this case, according to a second embodiment of my invention, vary the amount of water injected not only as a function of the delivery strokes, but also as a function of that or those of said pressure that is, or are, variable.

In all cases, it will be advantageous to inject an amount of water which is the more important as the ratio of the delivery and inlet pressures is higher, that is to say as the compression work to be effected is more considerable.

First, it will be assumed that only the delivery pressure varies and, further, that it is desired, for instance, to produce the injection of

water during the delivery stroke. In this case, I may arrange things in such manner that, as shown by the diagram of Fig. 5, the amount of liquid that is injected corresponds to a straight line $m-n$ or $m'-n'$ according as the pressure of delivery is equal to p or p' .

With this object in view, I may advantageously have recourse to the arrangement shown by way of example by Fig. 4.

10 The piston 7 of an injection pump 8 is controlled by a rod 15 bearing against an arm of an L-shaped piece 16, the other arm of which is connected, for instance through the intermediate of a lever 17, with the end of rod 3. The point 15 of contact of said rod 15 with piece 16 can be moved to a variable distance from the pivoting axis 18 of said piece 16 so that the amplitudes of the strokes of said piston 7 can be varied, which consequently varies the rate of delivery of said 20 pump 8.

I further provide, in order to control the displacements of rod 15, a device subjected to the action of the delivery pressure of the machine. This device may, for instance, consist of the system formed by a cylinder 19 and a piston 20, said piston being subjected, on one of its faces, to the action of spring 21, and on the opposite face, to the action of said delivery pressure, transmitted through a conduit 22. The whole is so devised that the point of contact of pieces 15 and 16 is more or less distant from the pivoting axis, 18, this distance increasing when said delivery pressure increases, or, in other words, the rate of delivery of the pump increasing when the delivery pressure increases.

It will be readily understood that such a system permits of varying the amount of liquid injected in proportion with both the amplitude of the strokes of the reciprocating parts and the delivery pressure, therefore with the mass of air delivered by the machine at every delivery stroke.

If, now, it is assumed that the feed pressure also varies, I may, in order to take account of these variations, cause said pressure to act, through the intermediate of a conduit 23, upon the other face of piston 20, so that the latter takes a position of equilibrium under the combined action of the delivery pressure and of the 50 suction pressure, the contacting point of levers 16 and 17 being the more distant from the pivoting axis 18 as the ratio of compression is higher, that is to say as the compression work to be supplied is more important.

But I may also, according to another embodiment of my invention, provide a system for effecting a complementary regulation of the rate of feed of injected liquid as a function of at least one of the working temperatures of the machine. For instance, in the following description, I will consider the variations of the temperature of the air sucked in into cylinder 1.

Preferably, in this case, I arrange things in such manner that the rate of feed of the liquid that is injected increases when the temperature of the feed air becomes higher.

In this way, it will be possible to maintain the temperature of the air that is delivered at a substantially uniform value, at least within certain limits of variation of the temperature of the surrounding air.

In this case also, in order to comply with these conditions, I may employ many different specific mechanisms. In particular, I may make use of the arrangement illustrated by Fig. 6 of the draw-

ings. In this embodiment of my invention, the rate of feed of the water injected into the compressor is controlled not only by the amplitudes of the delivery strokes and by the temperature of the feed air, but also by one of the working pressures of the machine, for instance by the feed pressure of cylinder 1.

Therefore, assuming, by way of example, that the delivery pressure remains substantially uniform and that the inlet pressure is variable, I must obtain a reduction of the amount of water injected into the compressor when said feed pressure increases, that is to say when the compression work to be effected is being reduced.

According to the embodiment shown by Fig. 6, the piston 7 of a pump 8 is controlled by a rod 15 one of the ends of which is pivoted to said piston and the other end of which bears against an arm of an L-shaped oscillating piece 16 the pivoting axis 18 of which is fixed and the other 20 arm of which is associated, for instance through a connecting rod 17, with a prolonged part of rod 3 integral with the piston rod. The point of contact between rod 15 and piece 16 may be more or less distant from the axis 16 in such manner as to permit of modifying the amplitude of the strokes of piston 7, and therefore the amount of water injected into the compressor, independently of the variations of the strokes of the compressor piston 2.

The displacements of rod 15 are controlled by a thermostatic device, such for instance as a deformable box 56, mounted along the path of the feed air, advantageously in conduit 54, which deformable box is connected to the other 30 (intermediate) point of said rod 15 through suitable kinematic means. These means consist, for instance of rods 57 and 58 which coact respectively with the ends of a bell crank lever 59, arranged in such manner that, when deformable 40 box 56 expands as a consequence of a rise of temperature of the feed air, rod 15 is moved away from axis 18, which causes the rate of feed of injected water to increase.

In order to permit a complementary regulation 45 of the injection rate as a function of variations of the feed pressure of the machine, the pivoting axis 60 of the bell crank lever 59 is carried by the end of the arm of a bent lever 61 which is pivotally mounted about a fixed axis 62 and 50 the other arm of which is connected, through the intermediate of a rod 63, with a barometric or similar deformable box 64 subjected to the action of said feed pressure, for instance connected to conduit 54, the whole being devised 55 in such manner that the expansions of said barometric deformable box (resulting from a rise of the feed pressure in conduit 54) produce a displacement of rod 15 such that the useful length of the lever arm extending from pivot 60 18 to the point of contact of rod 15 and piece 16 decreases, that is to say that the rate of injection also decreases.

In all cases, whatever be the embodiment that is chosen, I obtain a free piston auto-compressor 65 the compressor portion of which is cooled by a system of injection of water the operation of which results sufficiently clearly from the preceding description for making it unnecessary to give any supplementary explanations.

In any case, such an auto-compressor has, among other advantages, that of working with an optimum efficiency, at least within certain limits of variation of the pressure and temperature of the surrounding atmosphere.

The system above described may be used either in this state, or in combination with certain other characteristic arrangements, such as will be hereinafter described, and which may eventually be employed separately.

5 According to a supplementary feature, which will be supposed, in the following description, to be applied to the auto compressor partly shown by Fig. 4, I provide means for automatically controlling the beginning of the injection of cooling liquid into the compressor as a function of at least one of the characteristics of operation of the machine, for instance as a function of the inlet pressure.

15 With this object in view, I may advantageously, for instance as shown by Fig. 4, have the pivoting axis of piece 16 carried by the end of the rod of a piston 24 coating with a cylinder 25 in which the pressure is equal to the inlet pressure of the air fed to the machine. The variations of this pressure produce variations in the vertical position of said pivoting axis 18, and, consequently, variations of the time at which injection is started.

20 25 I might eventually provide an adjustment of the beginning of injection as a function of a factor other than the working pressure of the machine, for instance as a function of one of the working temperatures.

30 Of course, the parts which control the injection of air into the compressor are not necessarily cams carried by the rods of the compressor pistons, but they might be reciprocating parts of different structure and connection with the pistons, such for instance as oscillating connecting rods operative by the system which synchronizes the movements of the pistons.

35 On the other hand, as already above stated, the injection of water might be effected into the compressor portion of a free piston machine other than an auto-compressor, for instance an auto-generator, that is to say a machine having a single gaseous circuit.

40 45 In a general manner, while I have, in the above description, disclosed what I deem to be practical and efficient embodiments of the present invention, it should be well understood that I do not wish to be limited thereto as there might be changes made in the arrangement, disposition, and form of the parts without departing 50 from the principle of the present invention as comprehended within the scope of the appended claims.

What I claim is:

55 1. A free piston machine of the type described, which comprises, in combination, a compressor part, adjustable means for injecting liquid into said compressor part, and means, responsive to variations in the inlet pressure of the compressor part, for controlling the time of operation of said liquid injecting means as a function of said inlet pressure.

60 65 2. A free piston machine of the type described, which comprises, in combination, a compressor unit including at least one piston, adjustable means for injecting liquid into said compressor unit, and means operative by said last mentioned piston for controlling the working of said liquid injecting means as a function of the amplitude of the strokes of said last mentioned piston.

70 75 3. A free piston machine of the type described, which comprises, in combination, a compressor unit including at least one piston, a variable stroke pump for injecting liquid into said compressor unit, and means operatively connected

with said last mentioned piston for operating said pump so as to vary the delivery thereof as a function of the amplitude of the strokes of said last mentioned piston.

4. A free piston machine of the type described, which comprises, in combination, a compressor unit including at least one piston, a variable stroke pump fed with a cooling liquid, means for connecting the delivery of said pump with said compressor unit, for injection of said liquid from said pump into said compressor unit, a reciprocating member for operating said pump, and a cam rigid with said last mentioned piston for operating said reciprocating member in accordance with the amplitude of the strokes of said last mentioned piston.

5. A free piston machine of the type described which comprises, in combination, a compressor unit including at least one reciprocating piston, an accumulation pump fed with a cooling liquid, a reciprocating member included in said pump and the amplitude of the movement of which determines the delivery of said pump, a rod carried by said compressor piston, cam means rigid with said rod adapted to cooperate with said reciprocating member for controlling the amplitude of the displacements thereof in accordance with the amplitude of the displacements of said compressor unit piston, a passage connecting the delivery of said pump with said compressor unit, a valve for controlling said passage, and means operative by said compressor unit piston for controlling the opening of said valve.

6. A free piston machine of the type described, which comprises, in combination, a compressor unit, including at least one reciprocating piston, a variable stroke pump adapted to be fed with a cooling liquid, a reciprocating member included in said pump and the amplitude of the movement of which determines the delivery of said pump, means for connecting the delivery of said pump with said compressor unit, an axis, a part pivoted about said axis, operatively connected with said compressor piston for oscillating in accordance with the displacements of said reciprocating piston, a lever pivoted to the outer end of said reciprocating member and adapted to cooperate with said oscillating part for transmitting the movements thereof to said reciprocating member of the pump, and means operative by variations of pressure of at least one element of said compressor unit for controlling the position of said lever, so that it cooperates with different points of said oscillating member according to the corresponding values of said pressure.

7. A free piston machine of the type described, which comprises, in combination, a compressor unit, including at least one reciprocating piston, a variable stroke pump adapted to be fed with a cooling liquid, a reciprocating member included in said pump and the amplitude of movement of which determines the rate of delivery of said pump, means for connecting the delivery of said pump with said compressor unit, an axis, an L-shaped piece pivoted about said axis, a rod for said compressor piston, a connecting rod interposed between said rod and one branch of said L-shaped piece, a lever pivoted to the outer end of said reciprocating member of the pump and adapted to cooperate with the other branch of said L-shaped piece for transmitting the oscillations thereof to said reciprocating member of the pump, a cylinder having at least one closed end connected to the delivery of said compres-

5 sor, a piston movable in said cylinder, means for yieldingly opposing the action of the delivery pressure of said compressor on said last mentioned piston, and mechanical means for interconnecting said last mentioned piston with said lever, whereby the position of said lever is controlled by said delivery pressure of the compressor, so that said lever cooperates with different points of the second mentioned branch of said 10 L-shaped piece according to the value of said pressure.

10 8. A free piston machine of the type described, which comprises, in combination, a compressor unit, including at least one reciprocating piston, 15 a variable stroke pump adapted to be fed with a cooling liquid, a reciprocating member included in said pump and the amplitude of movement of which determines the rate of delivery of said pump, means for connecting the delivery of said 20 pump with said compressor unit, the last mentioned means including an atomizer for said liquid, whereby said liquid is introduced in the atomized state into said compressor unit, an axis, an L-shaped piece pivoted about said axis, a rod 25 for said compressor piston, a connecting rod interposed between said rod and one branch of said L-shaped piece, a lever pivoted to the outer end of said reciprocating member of the pump and adapted to cooperate with the other branch of 30 said L-shaped piece for transmitting the oscillations thereof to said reciprocating member of the pump, a cylinder having one closed end connected to the delivery of said compressor unit, and the other closed end connected to the inlet of said 35 compressor unit, a piston movable inside said cylinder, under the effect of the opposed actions of said delivery and inlet pressures of the compressor unit, and mechanical means for interconnecting said last mentioned piston with said lever, whereby the position of said lever is controlled by the combined actions of said pressures, so that said lever cooperates with different points of the second mentioned branch of 40 said L-shaped piece according to the values of said pressures.

45 9. A free piston machine of the type described, which comprises, in combination, a compressor unit, including at least one reciprocating piston, a variable stroke pump adapted to be fed with a cooling liquid, a reciprocating member included in said pump and the amplitude of the movement of which determines the rate of delivery of said pump, an atomizer opening into said compressor unit, means for connecting the delivery of said 50 pump with said atomizer, whereby atomized liquid is fed into said compressor unit, a fixed axis, a piece pivoted about said axis, mechanical means for connecting said piston with said pivoting piece, whereby the reciprocating movement of said piston produces an oscillating movement of said pivoting piece, a lever pivoted to the outer end of said reciprocating member of the pump and adapted to cooperate with said pivoting piece for transmitting the reciprocating movement 55 thereof to the reciprocating member of the pump, a member movable in response to variations of one of the characteristic temperatures of said compressor unit, and mechanical means for interconnecting said last mentioned member with said lever associated with said reciprocating member of the pump, whereby the relative position of said lever is controlled by the value of said temperature, so that said lever cooperates with different points of said pivoting piece ac-

ording to the values of said temperature, respectively.

10 10. A free piston machine of the type described, which comprises, in combination, a compressor unit, including at least one reciprocating piston, 5 a variable stroke pump adapted to be fed with a cooling liquid, a reciprocating member included in said pump and the amplitude of movement of which determines the rate of delivery of said pump, an atomizer opening into said compressor unit, means for connecting the delivery of said pump with said atomizer, whereby atomized liquid is fed into said compressor unit, a fixed axis, a piece pivoted about said axis, said piece being L-shaped, mechanical means for connecting one branch of said piece with said compressor unit piston, whereby the oscillating movement of said piston produces a rocking movement of said pivoting piece, a lever pivoted to the outer end of said reciprocating member 15 of the pump and adapted to cooperate with the other branch of said L-shaped piece for transmitting the oscillating movement thereof to said reciprocating member of the pump, a thermometric deformable box subjected to the temperature of the air fed to said compressor unit, and mechanical means for interconnecting a movable part of said deformable box with said lever, whereby the position of said lever is controlled by the value of said temperature, so that said 20 lever cooperates with different points of said pivoting piece according to the values of said temperature, respectively.

15 11. A free piston machine of the type described, which comprises, in combination, a compressor unit, including at least one reciprocating piston, a variable stroke pump adapted to be fed with a cooling liquid, a reciprocating member included in said pump and the amplitude of movement of which determines the rate of delivery of said 25 pump, an atomizer opening into said compressor unit, means for connecting the delivery of said pump with said atomizer, whereby atomized liquid is fed into said compressor unit, a fixed axis, an L-shaped piece pivoted about said axis, 30 mechanical means for connecting one branch of said L-shaped piece with the piston of said compressor unit, whereby the oscillating movement of said piston produces a rocking movement of said pivoting piece, a lever pivoted to the outer end of said reciprocating member of the pump and adapted to cooperate with the other branch 35 of said L-shaped piece for transmitting the oscillating movement thereof to said reciprocating member of the pump, a thermometric deformable box subjected to the temperature of the air fed to said compressor unit, mechanical means, including at least one lever and a pivoting axis for 40 said last mentioned lever, for interconnecting a movable part of said deformable box with said lever, whereby the position of said first mentioned lever is controlled by the value of said 45 temperature, so that said lever cooperates with different points of said pivoting L-shaped piece according to the value of said temperature, respectively, a barometric deformable element responsive to variations of pressure of the air fed to said compressor unit, and means operative by deformations of said barometric element for controlling the position of the last mentioned axis, 50 whereby the position of the first mentioned lever is further influenced by said pressure.

55 12. A free piston machine of the type described, which comprises, in combination, a compressor unit, including at least one reciprocable piston, 60

a variable stroke pump adapted to be fed with a cooling liquid, a reciprocable member included in said pump and the amplitude of movement of which determines the rate of delivery of said pump, an atomizer opening into said compressor unit, means for connecting the delivery of said pump with said atomizer, whereby atomized liquid is fed into said compressor unit, a movable axis, an oscillating piece pivoted about said axis, mechanical means for connecting said piece with the piston of said compressor unit, whereby the oscillating movement of said piston produces a rocking movement of said pivoting piece, means for interconnecting said oscillating piece with 5 said reciprocating member of the pump, whereby the movement of said piston is transmitted to said reciprocating member of the pump, a part movable vertically in response to variations of one of the functional factors of said compressor 10 unit, and means for displacing said axis in connection with the vertical displacements of said last mentioned part, whereby the time at which the injection of cooling liquid by said pump into said compressor unit starts varies in accordance 15 with variations of said functional factor.

13. A free piston machine of the type described, which comprises, in combination, a compressor unit, including at least one reciprocating piston, a variable stroke pump adapted to be fed with a 20 cooling liquid, a reciprocating member included in said pump and the amplitude of movement of which determines the rate of delivery of said pump, an atomizer opening into said compressor unit, means for connecting the delivery of said 25 pump with said atomizer, whereby atomized liquid is fed into said compressor unit for each stroke of said pump, a movable axis, an L-shaped piece pivoted about said axis, mechanical means for connecting one branch of said L-shaped piece with 30 the piston of said compressor unit, whereby the oscillating movement of said piston produces a 35 rocking movement of said pivoting piece, a lever pivoted to the outer end of said reciprocating member of the pump and adapted to cooperate 40 with the other branch of said L-shaped piece for transmitting the oscillating movement thereof to 45 said reciprocating member of the pump, a part movable in response to variations of at least one 50 of the functional factors of said compressor unit, mechanical means for connecting said part with an intermediate point of said lever, whereby the 55 position of said lever is controlled by the value of said functional factor, so that said lever cooperates with different points of said L-shaped pivoting piece and the stroke of said pump varies according to the values of said functional factor, respectively, a part movable vertically in response to variations of one of the functional fac-

tors of said compressor unit, and means for displacing said movable axis operative by the displacements of said last mentioned part, whereby the time at which injection of cooling liquid by said pump into said compressor unit starts varies in accordance with variations of said functional factor. 5

14. A free piston motor compressor which comprises, in combination, a motor part and a compressor part, adjustable means for injecting non-combustible liquid in said motor compressor and means responsive to variations of length of the free piston stroke for controlling the working of said liquid injecting means so as to vary the rate of injection of said liquid into said motor compressor. 10

15. A free piston motor compressor, according to claim 14, further comprising means responsive to variations of at least one of the pressures of operation of said motor compressor, said last 20 mentioned means controlling together with said piston stroke responsive means said liquid injecting means so as to vary the rate of injection of said liquid into said motor compressor.

16. A free piston motor compressor, according to claim 14, further comprising means responsive to variations of the fluid inlet pressure to said motor compressor, said last mentioned means controlling together with said piston stroke responsive means said liquid injecting means so as to vary the rate of injection of said liquid into 25 said motor compressor.

17. A free piston motor compressor, according to claim 14, further comprising means responsive to variations of the delivery pressure of said motor compressor, said last mentioned means controlling together with said piston stroke responsive means said liquid injecting means so as to vary the rate of injection of said liquid into 30 said motor compressor. 40

18. A free piston motor compressor, according to claim 14, further comprising means responsive to variations of at least one of the temperatures of operation of said motor compressor, said last 45 mentioned means controlling together with said piston stroke responsive means said liquid injecting means so as to vary the rate of injection of said liquid into said motor compressor.

19. A free piston motor compressor, according to claim 14, further comprising means responsive to variations of the temperature of the air fed to said motor compressor, said last mentioned means controlling together with said piston stroke responsive means said liquid injecting means so as to vary the rate of injection of said liquid into 50 said motor compressor. 55
